UNITED STATES PATENT OFFICE.

GEORGE H. ELLIS, OF ST. PAUL, MINNESOTA.

COMPOSITE LATH AND HEAT-INSULATING MATERIAL.

1,228,422.

Specification of Letters Patent. Patented June 5, 1917.

Application filed June 18, 1915. Serial No. 34,831.

To all whom it may concern:

Be it known that I, GEORGE H. ELLIS, a citizen of the United States, residing at St. Paul, in the county of Ramsey and State of Minnesota, have invented certain new and useful Improvements in Composite Lath and Heat-Insulating Materials; and I do hereby declare the following to be a full, clear, and exact description of the invention, such as will enable others skilled in the art to which it appertains to make and use the same.

My present invention has for its particular object the provision of an improved composite lath and heat insulating material, and is in the nature of a modification of or improvement on the composite lath and heat insulating material disclosed and broadly claimed in my prior Patent 1,126,187, of date, January 26, 1915.

20 The salient novel feature of the present invention consists in making the lath of a hard vegetable fiber or paper board. This material used as a lath is very strong, does not expand or contract under varying moisture to any material extent and does not rot, is very tough and strong, has the desired flexibility required for many purposes, and generally stated, is free from the many objections found in wooden lath, and furthermore, may be produced at less cost than could wooden lath.

25 The invention is illustrated in the accompanying drawings wherein like characters indicate like parts throughout the several views. Referring to the drawings:

Figure 1 is a perspective view with some parts sectioned and some parts broken away, showing one form of the fiber lath applied to a heat insulating material; and.

30 Fig. 2 is a similar view illustrating a somewhat modified form of the fiber lath.

In Fig. 1, the numeral 1 indicates a heat insulating material, the numeral 2 a water-proof facing therefor, and the numeral 3 a fiber lath. Preferably, the insulating material 1 is in a flexible felted sheet such as that disclosed and claimed in Letters Patent of the United States, No. 908,681, granted to James E. Lappen, of date, January 5th, 1909, and entitled "Flax felt", but the said insulating material may take various other forms and might, for example, be composed

of shredded straw, corn stalks, hemp, excelsior, shavings, and the like. The water-proof facing is preferably a heavy paper known to the trade as "Neponset" paper. The fiber lath shown in Fig. 1 are each complete individual members or solid bodies formed with beveled edges so that the opposing undercut or beveled edges of adjacent lath form a dove-tail channel into which portions of the plaster 4 will be forced to securely anchor the plaster to the said lath. The lath are placed directly against the water-proof facing 2 and are secured thereto and to the heat insulating material 1, preferably by nails 5 driven therethrough and having their ends clenched on the faces of the lath.

The construction as illustrated in Fig. 2 is like that illustrated in Fig. 1, except as to the form of the fiber lath, the latter in this instance being made up, each of a relatively narrow inner strip 6 and a relatively wide outer strip 7. The narrow inner strips 6 are preferably much thicker than the outer strips 7 and the latter are placed thereon with both edges projecting, so that the opposing undercut edges of adjacent lath form an angular dove-tail channel into which portions of the plaster 4 will run. In this construction, the nails 5 are driven through the insulating material 1, through the water-proof facing 2 and through both lath forming sections 6 and 7 and are clenched on the face of the latter, thereby securely fastening all of the said parts together.

The vegetable fiber lath will not split as will wooden lath, and hence, afford a much better material against which to clench the ends of the metallic fastening devices.

What I claim is:

1. A composite lath and heat insulating material comprising a felted flexible insulating sheet, and a vegetable fiber board lath secured thereto.

2. A composite lath and heat insulating material comprising a flexible insulating body sheet, a water proof facing applied thereto, vegetable fiber board lath applied to said water proof facing; and metallic fastening devices driven through said three elements and clenched against said lath.

3. A composite lath and heat insulating

2

material comprising a flexible insulating body sheet, a water proof facing applied thereto, vegetable fiber board lath applied to said water proof facing, and metallic fastening devices driven through said three elements and clenched against said lath, the edges of said lath being undercut.

In testimony whereof I affix my signature in presence of two witnesses.

GEORGE H. ELLIS.
